(57) **CLAIM**

I claim the ornamental design for exterior track assembly having slidably adjustable mounts for decorative lights, as shown and described.

DESCRIPTION

FIG. 1 is a perspective view of an exterior track assembly having slidably adjustable mounts for decorative lights embodying the design of the present invention.

FIG. 2 is a front elevational view thereof;

FIG. 3 is a rear elevational view thereof;

FIG. 4 is a left side elevational view thereof, the right side elevational view being a mirror image thereof; and,

FIG. 5 is a top plan view thereof.

1 Claim, 3 Drawing Sheets

FIG. 1.

FIG. 2.

FIG. 4.

FIG. 3.

FIG. 5.
